United States Patent Office

Des. 230,828
Patented Mar. 19, 1974

230,828

BOTTLE

Simon Jeruchim, Pomona, N.Y., assignor to Helena Rubinstein, Inc., New York, N.Y.

Filed Apr. 24, 1972, Ser. No. 247,232

Term of patent 14 years

Int. Cl. D9—01

U.S. Cl. D9—168

FIG.1

FIG.3

FIG. 1 is a side perspective view of a bottle showing my new design;

FIG. 2 is an end perspective view; and

FIG. 3 is a top plan view thereof.

The side and end not shown are the same in appearance as the side and end shown.

I claim:

The ornamental design for a bottle, as shown and described.
